UNITED STATES PATENT OFFICE.

JOHN K. O'NEIL, OF TROY, NEW YORK.

HORSESHOE.

SPECIFICATION forming part of Letters Patent No. 236,353, dated January 4, 1881.

Application filed April 8, 1880. (Model.)

To all whom it may concern:

Be it known that I, JOHN K. O'NEIL, of Troy, in the county of Rensselaer and State of New York, have invented an Improved 5 Horseshoe; and I do hereby declare that the following is a full and exact description thereof, reference being had to the accompanying drawings, making part of this specification—

Figure 1 being a view of the under side of 10 the shoe with my improvements; Fig. 2, a front view of the same; Fig. 3, a vertical section in a plane indicated by the line $x\ x$, Fig. 1; Fig. 4, a vertical section in a plane indicated by the line $y\ y$, Fig. 1; Fig. 5, a partial 15 horizontal section in a plane indicated by the line $z\ z$, Fig. 3.

Like letters designate corresponding parts in all the figures.

Let A represent the body of the horseshoe, 20 B the front or toe calk, and CC the heel-calks.

The first feature of my invention consists in an improved means of attaching the toe-calk to the body of the horseshoe, whereby security, strength, and durability are attained, and 25 the calk can readily be removed while the shoe remains on the horse's foot for sharpening, and as readily be reattached. A socket, D, is formed on the under side of the toe of the shoe to receive and inclose the shank a of the 30 calk. The socket extends horizontally back from near the front edge of the shoe, being preferably, but not necessarily, narrowed or tapered from the entering end to the other, so that the shank of the calk, having the same

35 form, may wedge tightly into it, and the edges might be dovetail in form; but this is no part of my invention. The calk-shank is inserted from the front till the front of the calk is about flush with that of the body of the shoe. A

40 part of the thickness of the socket is or may be taken from the thickness of the shoe-body, and, in fact, the under covering-bar, b, of the socket may be all taken from the thickness of the shoe-body, so that little or nothing is added 45 to the weight of the shoe in making the socket, and the bar of the socket projects as little as possible from the under surface of the shoe. This construction also enables me to adopt my peculiar mode of fastening the toe-calk in the 50 socket, which is another feature of my invention, and is substantially as follows:

A cross-groove, c, is formed in the lower

surface of the shank of the toe-calk, as shown in Figs. 1 and 3, and side holes, d d, are made into the socket to give entrance to a cross-key, E, for holding the calk by resting in the groove c. To retain this key securely in place it is made flexible, so that its ends will sink into depressions f f in the body of the shoe, outside of and under the holes d d, and the 60 lower surface of the key is rounded or chamfered at the ends, or essentially only at the rear entering end, as at g, Fig. 4, so that to withdraw the key the end must be forcibly made to rise over the sloped end h of the depression f. A notch or catch, i, may be formed in the upper surface of this projecting end of the key, to enable a suitable instrument to take hold of the key for withdrawing it. This construction, besides securely holding the key in 70 place, also sinks it within the under surface of the shoe-body, so that it will not be injured by striking anything or worn off by abrasion.

The next feature of my invention consists in a peculiar form of heel-calk, C, substantially 75 as represented. The lower extremity is composed of two sharp edges, l m, crossing each other, with notches or depressions between adjacent edges. This construction, while equally sharp, to hold from slipping, as a straight-edged calk, furnishes a greater length of bearing-edge, to prevent too much indentation in pavements, ice, &c., also is equally effectual 80 against slipping in all directions, and it also enables the calk to be quickly and easily 85 sharpened by filing in the notches.

The mode represented for securing the heel-calks in the body of the shoe is as follows: The shank n of the calk, whether round or square, is somewhat tapering, and it fits into 90 a corresponding socket or hole through or in the body of the shoe tightly by being a little too large for the socket, so that it does not enter therein quite to the shoulder of the calk. Thus every step of the horse tends to tighten 95 rather than loosen the calk in place. Then a cross-groove, p, is made in the calk-shank, as shown in Fig. 5, and a cross horizontal hole, r, is made through the body of the shoe, coinciding with the cross-groove p. One end, 100 preferably the inner end, of this hole is extended laterally, as at s, and a nail or key having been driven from the other side of the shoe-body through the hole and in the cross-

groove *p* of the calk till the inner end thereof projects through, say, a quarter of an inch, more or less, then this end is clinched down into the groove or depression *s*. The key or nail 5 is preferably crescent or otherwise roughened on the sides to obviate any tendency to work loose or out.

It may be here stated that my improved means of securing the toe-calk to the shoe is 10 not confined to the construction described of a complete inclosing socket for holding the shank thereof, since it may only partially cover the under side of the same, with a good but not so perfect a result.

15 What I claim as my invention, and desire to secure by Letters Patent, is—

1. The combination of the toe-calk *B*, pro-
vided with the shank *a*, and the horizontal

socket *D* of the shoe-body, substantially as and for the purpose herein specified. 20

2. The combination of the key *E* with the socketed horseshoe-body *A* and toe-calk *B*, the said key being arranged to fit in holes *d d* in the sides of the socket *D*, in depressions *f f* of the body, and in a cross-groove, *c*, of the 25 toe-calk, substantially as and for the purpose herein specified.

3. A heel-calk, *C*, formed with cross-edges *l m*, substantially as and for the purpose herein specified. 30

The above specification signed by me this 17th day of December, 1879.

JOHN K. O'NEIL.
